United States Patent Office.

ROBERT DICK, OF BUFFALO, NEW YORK.

Letters Patent No. 76,722, dated April 14, 1868.

IMPROVEMENT IN PRINTERS' CHASES.

The Schedule referred to in these Letters Patent and making part of the same.

TO ALL WHOM IT MAY CONCERN:

Be it known that I, ROBERT DICK, of the city of Buffalo, in the county of Erie, and State of New York, have invented an Improvement in the Method of Locking up Forms, the object being to meet and satisfy three wants, which have unceasingly forced themselves on the attention of printers as important desiderata:

First. The means of locking as large a form as a chase will hold without having anything between it and the type, and thicker than a long primer reglet, and, with the chase thus completely filled, to lock it up as quickly, easily, and permanently as in the common way; with the necessarily much larger chase, demanding, in turn, a larger press.

Second. The means of locking up forms so methodically as to obviate the necessity of delay in selecting quoins, and all difficulty in getting them out when driven hard and tight into the corner of the chase.

Third. The means of locking up forms of type without ever having the chase raised from the stone by the process of driving the quoins.

That all interested may know how my invention doth compass these objects, and, if skilled in art, achieve them, with all the accruing benefits, I do hereby declare that the following is a full and exact description thereof, reference being had to the accompanying drawing and representations, forming part of this specification.

Let Figure 1, in the drawing, represent a printers' form, locked and ready for the pressman, in which A A A A represent the chase, and the whole of the enclosed blocked plates and wooden furniture the same area of set type, with nothing whatever between it and the iron chase except the long primer iron reglets B B and B' B' along its side and foot, the type and these two reglets completely filling up the chase when the form is not locked, in which case the quoins q q q q lie loose in pairs, head to head, in the deepest part of the niches E E E E, formed in the chase along its side and foot. In locking up the form, these thin iron quoins are driven in the direction of their sharp ends, wedging the iron reglets against the type till the mass is so tightly locked together that no type can move.

In Figure 2, on the drawing, representing one of the iron wedges or quoins, let H H represent the wedge proper, and F F a flange formed on its upper edge, wide enough to suspend the quoin on the upper edge of the chase or iron reglet, but not wider than the eighth of an inch, the thickness of the iron reglet, lest the flange should touch the type in the process of locking up the form. This flange necessarily prevents the quoin, however carelessly driven, from ever touching the stone, so as to raise or warp the chase; and further, this flange being always, and at both ends, perfectly accessible to the shooting-stick, and being one body with the quoin, it is plain that driving the flange drives the quoin, and hence by it the quoin can at any time be instantly driven forward, and just as quickly back, even when driven tight and hard into the corner of the chase.

It is now manifest that, give a printer a form of any size, and one of my improved chases, only an eighth of an inch each way larger than the form, and, with the chase and the form, the proper complement of iron reglet and of my flanged quoins, and he can, without a moment lost in selecting quoins, lock up every such form most methodically, without once warping a chase by the violent contact of quoin and stone. If the chase given him be a common one, with all its sides rectilinear, it must be, each way, a quarter inch larger than the form; then, with the complement of iron reglet, as before, and a double quantity of my flanged quoins, one-half of them to be pressed down with the fingers between the iron reglet and the chase, so as to form inclined planes, to represent those formed by the niches in my improved chase; then let the other half of the flanged iron quoins be pressed in like manner, and so that the thin end of each one shall overlap a thin end of one of the others, and it is plain that, with the shooting-stick, the printer can complete the locking up of the form, in every such case, by this second mode, with results altogether similar to the first; to insure which, my iron quoins are flanged only on one side, and always on the same side, so as to admit of their being driven past each other when reversed. This double use of my flanged metallic quoins is shown at K K K K, in fig. 1 on the drawing.

What I claim as my invention, and wish to secure by Letters Patent, is—

1. The construction and use of a sufficient number of suitably-inclined planes, formed along the side and foot of otherwise common chases, employed in combination with thin wedges of any suitable substance, operating between these inclined planes and a reglet of suitable material, so as to lock up a form in an eighth of an inch of chase room as easily and as efficiently as in two inches of chase room, all constructed and operating in combination, substantially as set forth.

2. The flanged quoin or wedge, constructed and operated substantially as set forth.

ROBERT DICK.
